UNITED STATES PATENT OFFICE.

ROBERT V. BINGAY, OF PITTSBURGH, PENNSYLVANIA, ASSIGNOR TO PITTSBURGH TRANSFORMER COMPANY, A CORPORATION OF PENNSYLVANIA.

TRANSFORMER TANK.

Application filed March 7, 1923. Serial No. 623,834.

This invention relates to tanks for oil cooled electrical apparatus, such as transformers, and particularly to expansion means receiving the overflow of oil from the main tank due to the heating of the apparatus in service. The chief object of the invention is to protect the oil in the expansion tank from an accumulation of moisture by heat applied to the expansion tank to drive off the moisture and prevent it from depositing in the oil. Further objects of the invention particularly in protecting the expansion tank from freezing in cold weather will appear from the following specification taken in connection with the accompanying drawings, in which—

Fig. 1 is a diagram showing in outline a vertical sectional view of a transformer tank illustrating the invention.

Fig. 2 is a section on line 2—2 of Fig. 1, and

Figs. 3 and 4 are vertical sectional views of modified forms of expansion tanks.

In the specific embodiment of the invention shown in the drawings a main tank 5 containing a transformer immersed in oil is provided with an expansion tank 6 connected to the main tank by a pipe 7 so that when the transformer heats up in operation the expanding oil will pass through this pipe 7 into the expansion tank 6. The tank 6 is rectangular in cross section as shown in Fig. 2 so that a protective float 8 on the surface of the oil may freely rise and fall with the oil level. The top of the tank 6 has a removable cover 9 fastened in place by clamps 10 and carrying a breather connection 11 keeping the air space 19 over the oil in the expansion tank at atmospheric pressure.

In order to protect the oil in the expansion tank 6 from the accumulation of moisture from the air above it, the expansion tank is provided with heating means located preferably at the bottom of the tank as shown in Fig. 1 or adjacent that part of the tank which is specially formed to trap the moisture as shown in Fig. 3 or in the air space 19 above the oil as indicated in Fig. 4.

In the drawings this heating means is diagrammatically illustrated as comprising an electric heating element 12 in a tubular compartment 13 running along the bottom of the tank 6, this element 12 being supplied with current from a winding 14 of a small transformer 15, the primary winding 16 of which

may for example be connected into the secondary transformer circuit as shown.

The heat for the heating element may be supplied in any other convenient way, as for instance by a steam connection where a steam main is available. In the system shown in the drawings a portion 20 of the primary winding 16 of the transformer 15 is in series with the secondary circuit from the secondary winding 18 of the main transformer, indicated diagrammatically in Fig. 1, so that normally no current will flow through this portion 20 when there is no secondary load. Another connection 17 from the remainder 21 of this primary winding 16 connects this remaining portion 21 across a few coils of the secondary 18 of the main transformer to supply current to at least a portion of the winding 16 at all times. The relative sizes of the portions 20, 21 and the primary winding 16 of the heating transformer may be varied depending upon the effect desired, and either of these portions of the winding may be omitted.

The degree of heating is such that the moisture is driven out and prevented from depositing or accumulating in the oil in the expansion tank so that when this oil returns to the main tank upon cooling of the latter it will be dry and free from moisture. The float 8 protects the surface of the oil in the expansion tank 6 from contact with the air in the space 19 above it and avoids oxidation of the oil in the expansion tank. A plurality of heating tubes 13 may be used as indicated in Fig. 2 distributed as desired in the tank 6.

The breather 11 is preferably supplied with filtering material 22 through which the air must pass in going into and out of the space 19. The heating of the oil in the tank 6 also heats the air in the space 19 above the surface of the oil so that the air driven out through the filtering material 22 is heated and thoroughly dries this filtering material of any previously accumulated moisture. A further protection against the presence of moisture in the oil of the expansion tank is the trap 30 provided by the plate or partition 27 extending across the tank and positioned beneath the entrance opening of the breather 11. This plate is preferably inclined leading to a sump 28 drained by a cock 29. This trap partition 27 forms an isolated chamber above it which tends to

catch any moisture and particularly any moisture entering through the breather connection 11 and prevents it from entering the oil.

- 5 In the modification illustrated in Fig. 3 the expansion tank 6 is provided with a sump chamber 26 below the bottom of the tank so that any moisture will tend to gravitate into this sump chamber. Moisture in 10 such a chamber is in constant contact with the oil with a tendency to recontaminate it and with transformers exposed outside in cold weather there is constant danger of this moisture freezing and by its expansion breaking open the expansion tank. By the addition of a heating coil 32 in the heating chamber 33 around this sump chamber this sump chamber may be warmed so as to prevent the freezing of its contents or further heated so 20 as to drive off the moisture and prevent it from accumulating. The terminals of this heating coil 33 are preferably connected to the secondary of a heating transformer similar to that shown at 15 in Fig. 1.
- 25 In Fig. 4 the heating tube 43 is located in the air space 19 above the surface of the oil in the tank 6 heating this air and warming the tank so as to drive off and prevent the deposit of moisture. Upon the rise of the 30 level of the oil the heated air in space 19 is driven out through the filtering material 22 and breather 11 thoroughly drying this material so that upon the subsequent contraction of the oil and the lowering of its level 35 in the expansion tank the air passing into the space 19 will be thoroughly dried by this filtering material.

While this invention has been illustrated in connection with specific embodiments 40 shown in the drawings, it is not confined thereto. The heating element, for instance, may be placed in any desired position in the expansion tank and the degree and variation of the heating effect regulated in any preferred manner, or other modifications may be resorted to within the scope of the appended 45 claims.

I claim:—

1. The combination with an auxiliary expansion tank for the overflow of oil from a transformer tank, of heating means for heating a portion of said expansion tank, and a protective float member floating on the surface of the oil in said expansion tank.
- 55 2. An auxiliary expansion tank for the overflow of oil from the transformer tank, comprising a tank body, heating means there-

for, and a breather connection from the interior of said expansion tank to the air, said breather comprising a filtering material to exclude moisture from said tank.

3. An auxiliary expansion tank for the overflow of oil from the transformer tank, comprising a tank body, heating means therefor, a breather connection from the interior 65 of said expansion tank to the air, said breather comprising a filtering material to exclude moisture from said tank, and a protective float member adapted to freely float on the surface of the oil in said expansion 70 tank.

4. In an expansion tank for the overflow of oil from a main transformer tank the combination with means forming an air space above the level of the oil in said expansion tank, of a trap chamber adapted to collect moisture from said space so as to prevent it from entering said oil.

5. In an expansion tank for the overflow of oil from a main transformer tank the combination with means forming an air space above the level of the oil in said expansion tank, a breather connection maintaining said space in communication with the atmosphere, and a moisture trap chamber within said expansion tank and beneath the entrance of said breather connection adapted to collect moisture so as to prevent it from entering the oil in said expansion tank.

6. The combination with a tank adapted 90 to contain cooling oil for a transformer, of heating means in the oil of said tank, a space above the level of the oil in said tank, and a trap chamber adapted to collect moisture from said space so as to prevent it from entering said oil.

7. The combination with an auxiliary expansion tank for the overflow of oil from the transformer tank, of heating means within the oil of said tank, a space above the level 100 of the oil in said expansion tank, and a trap chamber adapted to collect moisture from said space so as to prevent it from entering said oil.

8. In an expansion tank for the overflow 105 of oil from the main transformer tank, the combination with means forming a space above the level of the oil in said expansion tank, heating means in said expansion tank, and a trap chamber adapted to collect moisture from said space so as to prevent it from 110 entering said oil.

ROBERT V. BINGAY.
